Primary Examiner — Karen E Eldridge Powers*(74) Attorney, Agent, or Firm* — Nath, Goldberg & Meyer;
Jerald L. Meyer**CLAIM**

The ornamental design for a necktie, as shown and described.

DESCRIPTION

FIG. 1 is an enlarged perspective view of a necktie;

FIG. 2 is a top plan view thereof; and,

FIG. 3 is a bottom plan view thereof.

The broken lines showing in the drawing disclosure illustrate unclaimed features of the article to which the design is applied.
